ROADWAY SHOULDER RETAINER

Ernest E. Nyvall, Seattle, Wash.

Application February 3, 1941, Serial No. 377,250

3 Claims. (Cl. 94—31)

This invention relates to roadway shoulder retainers, and has for one of its objects the production of a simple and efficient retainer which will eliminate the expensive upkeep of shoulders along roadways, and behind the shoulders in a solid, safe condition, thereby preventing washouts along the edges of the road.

A further object of this invention is the production of a simple and efficient retainer which is so constructed as to permit the paving of a highway to extend to the very edge of an embankment and thereby eliminate the necessity of maintaining earthen or other type shoulders, in this way adding additional usable surface to the road.

Other objects and advantages of the present invention will appear throughout the following specification and claims.

In the drawing:

Figure 1 is a transverse sectional view through a portion of a roadbed, showing the shoulder retainer in position;

Figure 2 is a fragmentary top plan view of a portion of the shoulder retainer;

Figure 3 is a transverse sectional view taken on line 3—3 of Figure 2;

Figure 4 is a longitudinal sectional view taken on line 4—4 of Figure 2;

Figure 5 is a perspective view of one of the shoulder-retainer sections;

Figure 6 is a fragmentary perspective view of one of the locking tongues;

Figure 7 is a side elevational view of one end of the flare board, showing one of the locking tongues in a locking position.

By referring to the drawing, it will be seen that 10 designates the body of the retainer plate which may be formed of a plurality of overlapping sections to provide a continuous retainer plate of a desired length. The body 10 comprises a preferably relatively flat sheet metal structure which is adapted to lie longitudinally under the road surface 11 and to be embedded in the roadbed 12 in the manner shown in Figures 1 and 3. The body 10 is preferably reinforced transversely by means of a pressed bead portion 13 and a suitable number of these bead portions may be used throughout the length of the body 10. The body 10 is provided at its rear edge with a plurality of slits 14 for defining tongues, certain portions of the body between the slits 14 being bent downwardly to provide the right-angularly extending anchoring tongues 15 and alternately spaced substantially horizontally extending tongues 16. The fill of the roadbed by

fitting between and around the tongues 15 and 16 will tend to hold the body 10 in an anchored position.

The outer edge of the body 10 is preferably bent upwardly and rearwardly at an incline of approximately 45 degrees to provide a flare board 17, which flare board is provided at its outer and upper edges with an outwardly rolled bead 18, which outwardly rolled bead is adapted to abut against the edge of the road surface 11 shown in Figures 1 and 2. The flare board 17 is preferably bent at a suitable angle to conform with the incline of the road fill embankment 19, shown in Figures 1 and 3.

15 A plurality of bracing tongues 20 are struck from the body 10 and bent forwardly and upwardly at an angle of approximately 45 degrees, the upper ends of the tongues 20 being inserted through slots 21 of the flare board in the manner shown in detail in Figures 3 and 7. The outer ends of these tongues 20 are notched or slit as indicated at 22, to provide lips 23 which may be bent at right angles to the tongues 20 when the outer end of the tongues 20 have been extended through the slots 21 in the flare board 17 to hold the flare board 17 at a proper angle and prevent the flare board from being pushed away from the edge of the embankment 19 or the edge of the road surface 11. These lips 23 will provide a locking means to retain the flare board in its proper position as described above.

As shown in Figure 2, the roadway shoulder retainer for the purpose of facilitating assembly, shipment, and placement in position, is preferably made up of a plurality of sections, the ends of which overlap, and to anchor these sections in overlapped relation the tongues 20 may be placed together, as shown in Figure 3, and inserted through the apertures 21 in the overlapping portions of the sections of the body 10, thereby holding the sections together. It should be understood that if desired the retainer may be formed in one plate and in some instances it will only be necessary to utilize the length of 45 one plate to accomplish the desired object, this depending of course upon the topographical characteristics of the roadbed upon which the retainer is being used. It of course should be understood that the body 10 may be of any suitable or desired length and may be of any suitable or desired number of sections without departing from the spirit of the invention, a suitable number of tongues 20 being employed to properly brace the flare board throughout its length.

It should be understood that certain detail changes in the construction may be employed without departing from the spirit of the invention, so long as such changes fall within the scope of the appended claims.

Having described the invention, what is claimed as new is:

1. A roadway shoulder retainer comprising a relatively flat body having substantially horizontally extending anchoring tongues along one edge and right-angularly extending anchoring tongues arranged between the horizontally extending anchoring tongues, the outer edge of the body being upturned and rearwardly inclined to provide a flare board adapted to extend substantially flush with the edge of the embankment of the roadbed, the outer edge of the flare board being outwardly rolled to provide a reinforcing means and to constitute an abutment against which the road surface may rest whereby the road surface may be extended to the very edge of the embankment, reinforcing tongues carried by the body and being upwardly and outwardly inclined, said flare board having tongue-receiving means for receiving said reinforcing tongues, and means carried by the last mentioned tongues for locking the last mentioned tongues in engagement with said tongue receiving means.

2. A roadway shoulder retainer comprising a relatively flat body having substantially horizontally extending anchoring tongues along one edge and right-angularly extending anchoring tongues arranged between the horizontally extending anchoring tongues, the outer edge of the

body being upturned and rearwardly inclined to provide a flare board adapted to extend substantially flush with the edge of the embankment of the roadbed, the outer edge of the flare board being outwardly rolled to provide a reinforcing means and to constitute an abutment against which the road surface may rest whereby the road surface may be extended to the very edge of the embankment, reinforcing tongues carried by the body and being upwardly and outwardly inclined, said flare board having tongue-receiving apertures near the outer edge of the flare board, said reinforcing tongues having a plurality of laterally extending lips adapted to be bent at right angles to the last mentioned tongues to overlie the flare board and lock the flare board in a set angular position.

3. A roadway shoulder retainer comprising a plate, one edge of said plate having a flare board extending at an angle to the plate and providing a retaining means for the edge of the embankment of a roadbed and the edge of a road surface, reinforcing tongues carried by the body and being upwardly and outwardly inclined toward said flare board, said flare board having tongue-receiving apertures near the outer edge of the flare board for receiving the outer ends of said tongues, a plurality of laterally extending lips carried by said anchoring tongues near the outer ends of the tongues, the lips being adapted to be bent at an angle to the tongues to overlie the flare board and lock the flare board in a set angular position.

ERNEST E. NYVALL.
